UNITED STATES PATENT OFFICE.

EDWARD H. BUSCH, OF CHICAGO, ILLINOIS, ASSIGNOR TO WEBER COSTELLO COMPANY, OF COOK COUNTY, ILLINOIS, A CORPORATION OF ILLINOIS.

DESIGN FOR A BASE FOR TERRESTRIAL AND CELESTIAL GLOBES AND THE LIKE.

Application filed March 3, 1922. Serial No. 1,004. Term of patent 14 years.

To all whom it may concern:

Be it known that I, EDWARD H. BUSCH, a citizen of the United States, residing at Chicago, in the county of Cook and State of Illinois, have invented a new, original, and ornamental Design for a Base for Terrestrial and Celestial Globes and the like, of which the following is a specification, reference being had to the accompanying drawing, forming a part thereof.

Fig. 1 is a side elevation of my design and Fig. 2 is a plan view thereof.

I claim:—

The ornamental design for a base for terrestrial and celestial globes and the like, substantially as shown.

EDWARD H. BUSCH.
